US00D697293S

(12) **United States Design Patent**
Vestuti et al.

(10) **Patent No.:** **US D697,293 S**
(45) **Date of Patent:** **** Jan. 14, 2014**

(54) **SHOE**(71) Applicant: **Reebok International Limited**, London (GB)(72) Inventors: **Ricardo Vestuti**, Providence, RI (US); **John S. Greenhalgh**, Foxboro, MA (US)(73) Assignee: **Reebok International Limited**, London (GB)(**) Term: **14 Years**(21) Appl. No.: **29/445,791**(22) Filed: **Feb. 15, 2013****Related U.S. Application Data**

(62) Division of application No. 29/375,660, filed on Sep. 24, 2010, now Pat. No. Des. 677,866.

(51) **LOC (10) Cl.** **02-04**(52) **U.S. Cl.**USPC ..... **D2/947**; D2/951; D2/954(58) **Field of Classification Search**

Primary Examiner — T. Chase Nelson*(74) Attorney, Agent, or Firm* — Sterne, Kessler, Goldstein & Fox P.L.C.(57) **CLAIM**

The ornamental design for a shoe, as shown and described.

DESCRIPTION

FIG. 1 is a side view of a shoe showing our new design;

FIG. 2 is another side view thereof;

FIG. 3 is a front view thereof;

FIG. 4 is a rear view thereof; and,

FIG. 5 is a bottom plan view thereof.

The broken lines in the Figures show environment for illustrative purposes only and form no part of the claimed design.

1 Claim, 5 Drawing Sheets(56)
